UNITED STATES PATENT OFFICE.

ALANSON P. BRUSH, OF FLINT, MICHIGAN.

DESIGN FOR AN AUTOMOBILE-BODY.

43,135.

Specification for Design.

Patented Oct. 15, 1912.

Application filed March 26, 1910. Serial No. 551,812. Term of patent 7 years.

To all whom it may concern:

Be it known that I, ALANSON P. BRUSH, a citizen of the United States, residing at Flint, in the county of Genesee and State of Michigan, have invented a new, original, and ornamental Design for Automobile-Bodies, of which the following is a specification, reference being had to the accompanying drawing, forming part thereof.

The figure is a side elevation showing my new design for an automobile body.

I claim:

The ornamental design for an automobile body, as shown.

ALANSON P. BRUSH.

Witnesses:

E. L. THURSTON,
A. J. HUDSON.
